George R. Owens Inventor

Amilton Backe

Attorney

UNITED STATES PATENT OFFICE.

GEORGE R. OWENS, OF JOLIET, ILLINOIS.

CAR REPLACER.

Application filed September 12, 1922. Serial No. 587,757.

To all whom it may concern:

Be it known that I, GEORGE R. OWENS, a citizen of the United States, residing at Joliet, in the county of Will and State of Illinois, have invented certain new and useful Improvements in a Car Replacer, of which the following is a specification.

This invention has relation to car replacers, and has for an object to provide 10 a device for the purpose of replacing cars upon a railroad track. It may be formed largely in one piece and is provided with grooves and guides to direct the flanges of the car wheels and guide the same upon the 15 rails, in a rapid and effective manner.

Another object of the invention is to provide a car replacer of the character above described, and embodying a main portion adapted to be placed against the rail upon 20 which the car wheels are to be rested, and a second portion pivotally secured to the main portion for movement relative thereto, whereby, said second portion may be engaged beneath the rail and the car replacer 25 thereby securely held in place after suitable fastenings are driven into the ties.

Another object of the invention is to provide a car replacer having the characteristics above described, and which is simple in construction and design, permitting the manufacture of the same at a low cost, and which is light in weight, consistent with the objects to be attained.

In addition to the foregoing, this invention 35 comprehends improvements in the details of construction and arrangement of parts to be hereinafter described and particularly pointed out in the appended claims.

In the accompanying drawings, in which 40 similar and corresponding parts are designated by the same characters of reference throughout the several views in which they appear:

Figure 1 is a view in plan of a car replacer constructed in accordance with my 45 invention.

Figure 2 is a view thereof inside elevation.

Figure 3 is a view in side elevation, looking at the side of the device opposite that 50 shown in the preceding figure.

Figure 4 is a view thereof in end elevation.

Figure 5 is a diagrammatic plan view of a portion of a railroad track, illustrating a pair of replacers in position upon the 55 rails for the purpose of rerailing a derailed truck; and,

Fig. 6 is a fragmentary vertical cross-sectional view, taken approximately on the plane indicated by the line 6—6 of Fig. 1. With reference to the drawings, 10 indicates the base portion which is rectangular when viewed in plan, and is formed on one longitudinal side with a base flange 11, apertured to receive spikes. The under side is formed with a longitudinally extending 60 groove 12 in which to receive the head of the rail when the car replacer is placed thereupon.

An integral flange 13 is formed upon the top of the device adjacent the outer longitudinal edge thereof and extending parallel to the rail. A second flange is formed at the opposite longitudinal edge of the device, as at 14, said flange extending at an angle to the longitudinal side of the same. A relatively broad, downwardly inclined portion is formed at one end of the device as at 15, while a relatively narrow, downwardly inclined portion 16 is formed at the other end. The flange 14 mentioned above is continued 80 along the edges of the inclined portions 15 and 16 as at 17 and 18 respectively.

A pair of longitudinally extending grooves 19 and 20 in parallel relation are formed in the upper surface of the base portion of the 85 device, defining a ridge 21 therebetween, one groove being located closely adjacent the flange 13. A second pair of grooves 22 and 23 are formed upon the surface of the device, said grooves being however extended 90 at an angle to the grooves 19 and 20 and intersecting the same, defining a ridge 24 therebetween. One of said inclined grooves is located closely adjacent the flange 14. It is to be noted that the ridge 21 is located in 95 contiguous relation to the ball of the rail and inclined portions 25 are formed at the ends of the ridge and thereby form a runway from the surface of the ball of the rail.

It is to be further noted that the ridge 24 100 is continued downward upon the surface of the inclined portion 15 as at 26, thereby defining a pair of parallel grooves 27 and 27' at opposite sides. Said grooves 27 and 27' merge into the grooves 22 and 23 to direct the flanges of the car wheels thereinto.

A plurality of apertured lugs 28 are formed upon the outer longitudinal side of the base portion of the device to enter the spaces between a corresponding number of 110 pairs of apertured ears 29 which are formed upon a longitudinally extending securing

member 30. Said securing member is substantially triangular in cross section and the upper side is extended into the groove 12 in the under side of the base portion of the device whereby to engage beneath the ball of the rail when the device is in place as shown in Figure 4 of the drawings. The said securing member is also formed at its base with a flange 31 whereby spikes may be inserted into the openings in said flange and the device thereby secured to the ties. Pins 32 are inserted into the apertures of the lugs 28 and ears 29 whereby to hingedly secure the securing member 30 to the base portion 15 of the device.

In placing the rerailer in position upon the rails, the hinged securing member 30 is first moved upwardly in a counter clockwise direction about its pivots 32, from its position shown in Fig. 4, whereupon the device is lowered into place, with the head of the rail entering the under groove 12. The securing member 30 is then swung downwardly again to the position shown in Fig. 4, with its toe engaging the under surface of the rail head, whereupon the re-railer may be secured in place by spiking the flanges 11 and 31 to the cross ties, as shown.

When the device is placed upon the rail in the manner shown and described, in conjunction with a duplicate placed upon the other rail as indicated in Fig. 5 it will be seen that the broad inclined surface 15 of one device will be located between the rails and the broad surface of the other device will be on the outer side of one of the rails. To replace a car upon the tracks, the flange of the wheel 40 at one side of the truck is placed in the groove 27' of the inclined portion 15 nearest the flange 17, while the other wheel 41 is placed in the other groove 27 of the other device. If the car is then urged upward the flange of the wheel 40 between the rails will enter the groove 23 and glide down the other incline 16 at the opposite end of the device, directing the tread of the wheel upon the ball of the rail and the flange of the wheel thereagainst. The flange of the wheel 41 at the other side of the truck will 50 enter the groove 22 and crossing over the

rail will enter the groove 19 and be thereby directed upon the rail with the wheel flange engaged against the inside of the ball of the rail. It will be seen that the flanges 13 and 14 form at the same time guides and safety devices to prevent the car wheel from leaving the car replacer when mounted thereupon.

While I have illustrated and described my invention with some degree of particularity, I realize that in practise various alterations therein may be made. I therefore reserve the right and privilege of changing the form of the details of construction or otherwise altering the arrangement of the correlated parts, without departing from the spirit of the invention or the scope of the appended claims.

Having thus described my invention what is claimed as new and desired to secure by Letters Patent is:

1. A car replacer including, a base portion adapted to straddle the rail and having a groove therebeneath to receive the ball of the rail, and a plurality of grooves formed upon its upper surface, some running parallel to the rail and others at an angle thereto, an inclined portion at each end of the device, one inclined portion being narrow and the other broad, said broad portion having grooves in its upper surface leading into the inclined grooves of the base portion, and a flange at one side of the base portion and at one side of the broad inclined portion.

2. A car replacer including, a base portion adapted to straddle a rail and having a groove therebeneath to receive the ball of the rail with one side of the device cut away to permit the device to be placed against the side of the rail and the ball readily engaged in the groove, and a securing member hingedly secured to the base portion and adapted to engage beneath the ball of the rail, said base portion and securing member having openings to receive spikes whereby to permit securing of the device to the ties.

In testimony whereof, I, affix my signature:

GEORGE R. OWENS.
